UNITED STATES PATENT OFFICE.

THOMAS LUCIEN TALIAFERRO, OF CHICAGO, ILLINOIS.

JAR-CLOSING MACHINE.

Application filed December 29, 1920. Serial No. 433,797.

To all whom it may concern:

Be it known that I, THOMAS L. TALIAFERRO, a citizen of the United States, residing at Chicago, in the county of Cook, State of Illinois, have invented certain new and useful Improvements in Jar-Closing Machines, of which the following is a description, reference being had to the accompanying drawing and to the figures of reference marked thereon.

The invention relates to new and useful improvements in jar closing machines, and more particularly to a machine for attaching a metal cap to a glass or porcelain jar. An object of the invention is to provide a machine of the above character, wherein devices are provided for causing the jar to travel in a curved path and while it is moving to reshape the flange of the metal cap, so as to secure it to the jar.

A further object of the invention is to provide a machine of the above character wherein the securing of the cap to the jar is brought about by means of a rotating curved member which engages the flange at one side of the mouth of the jar, and a stationary cam ledge curved to conform to said curved member and spaced therefrom which engages the flange of the cap at the other side of the mouth of the jar, and wherein said rotating member and said cam ledge are so disposed and constructed as to gradually turn the edge of the flange of the cap underneath the shoulder or ledge at the mouth of the jar.

A still further object of the invention is to provide a machine of the above type, wherein the closing means for securing the metal cap to the glass jar is so constructed as to support and convey the jar by engagement with the flange of the cap and the ledge at the mouth of the jar.

These and other objects will in part be obvious and will in part be hereinafter more fully disclosed.

In the drawings which show by way of illustration one embodiment of the invention—

Figure 1 is a plan view of a machine embodying my improvements;

Figure 2 is a front view of the same;

Figure 3 is a view on the line 3—3 of

Figure 1;

Figure 4 is a sectional view on the line 4—4 of Figure 1;

Figure 5 is a sectional view on the line 5—5 of Figure 1;

Figure 6 is a view similar to Figure 4, but showing a slightly modified form of rotating member and cam ledge for securing a cap of a different type to a jar;

Figure 7 is a view similar to Figure 6, but showing the cap as having been secured to the jar by the closing means;

In my copending application, Serial No. 433,796, filed of even date herewith, I have shown, described and claimed broadly a machine for securing metal caps to glass or porcelain jars, which includes a feeding means for the jar adapted to engage the flange of the cap and the flange at one side of the mouth of the jar, while a co-operating supporting ledge engages the flange of the cap at the opposite side thereof and operates to reshape the flange of the cap so as to secure the same to the jar. The present invention is directed to a modified form of the type of machine shown, described and claimed in my said copending application.

In the present form of the invention there is a central rotating member 1, which is circular in outline and consists of two disks 2 and 3. These disks are mounted on a vertical shaft 4. The shaft is mounted in suitable bearings 5 and 6 carried by the frame of the machine. Said frame consists preferably of supports 7, to which is secured a table 8 by means of bolts 9—9. The shaft 4 is provided with a collar 10 which carries the lower circular member 3. The upper circular member is keyed to the shaft and rotates therewith but is free to move endwise on the shaft. A spring 11 encircling the shaft 4 bears against the upper member 2 and normally forces the same downwardly into yielding contact with the lower member 3. A wing nut 12 threaded on to the shaft serves as an abutment for the spring 11 and as a means whereby the tension of the spring 11 may be varied.

Co-operating with the rotating member 1 is a curved cam 13. This cam is curved to conform in outline to the circular rotating member 1 and is spaced therefrom. Extending upwardly from the supporting table of the machine are three standards 14, 15

and 16. The curved cam 13 is carried by these standards. Each standard has a slot 17 and a clamping bolt 18 extending through the slot is threaded into the upper section 13^a of the cam 13. This serves as a rigid means for securing the member 13^a and permits the same to be adjusted vertically for different heights of jars. The lower member 13^b of the curved cam 13 is secured to the upper member 13^a by means of rods 19 which are threaded into the member 13^a and extend freely through openings in the lower member 13^b. These rods are threaded and provided with springs 20 and also with nuts 21 which serve as abutments for the springs and cause the springs to yieldingly force the member 13^b upwardly into contact with the member 13^a.

The shaft 4 carrying the circular member 1 is rotated by a suitable belt wheel 22. The cam 13 is curved or turned outwardly at 23, which is the receiving end of the machine. It is also curved or bent outwardly at 24, which is the delivery end of the machine. Between the receiving and delivering end of cam 13 there is a guiding plate 25. This guiding plate 25 is formed in two sections. The upper section 25^a is rigidly secured to a cross bar 26, which in turn is rigidly secured by bolts 27—27 to the ends of the cam member 13^a. The lower member 25^b is secured to the upper member 25^a by means of bolts 28, which are threaded into the upper member and extend through openings in the lower member and springs 29 carried by these bolts yieldingly force the lower member 25^b upwardly into contact with the upper member 25^a. This member 25^a is formed into two sections, as clearly shown in Figure 1, and each section is secured to the cross bar 26 by means of bolts 30, which pass through suitable slots in the cross bar and are threaded into the upper member 25^a. The purpose of these slots is to permit the two sections to be adjusted toward or from the ends of the cam 13 for changing the width of the space between these sections and the ends of said cam member.

Travelling in front of the machine is an endless belt 31 which runs over rollers 32—32, mounted on bracket arms 33—33, respectively. Extending over this endless conveyor and in part over the table 8 is a disk 34. Said disk 34 is rigidly carried by a shaft 35, mounted in a bearing 36 in the table 8, and the shaft 35 is driven by a suitable belt wheel 37. This disk is very thin and is provided with a knife edge. The jars on the conveyor 31, moving in the direction of the arrow in Figure 1, will be delivered on to the rotating disk. The disk rotating in the direction of the arrow shown in Figure 1 will carry the jars against the guiding arm 38 and into the space between the

the guiding member 25 and the end of the cam ledge 13. The member 25^a, as clearly shown in Figure 4, is formed with a recess 39, while the member 25^b is formed with a recess 40. The member 13^a is formed with a recess 41, while the member 13^b is formed with a recess 42. The recesses 39 and 40 are opposed to each other and likewise the recesses 41 and 42. These recesses together form a clearance space into which the cap 75 and the ledge of the jar pass.

In the drawings, I have indicated a jar at J, and said jar is provided with a shoulder or ledge 43. The metal cap is indicated at C and this cap is provided with a depending flange 44. It will be understood that the caps are placed loosely upon the jars before they enter the machine. The disk 34 rotating causes the jar to travel along the space between the cam ledge 13 and the guiding member 25, and when the point J¹ is reached, the flange of the cap will come into contact with the rotating member 1. This rotating member 1, as clearly shown in Figure 3, is provided with a recess 45. This recess 45 is formed in part in the member 2 and in part in the member 3 and is in alignment with the recesses formed in the guiding member 25. The upper and lower walls of the recesses 41 and 42, respectively gradually approach each other, as will be apparent from Figure 5, wherein the section is taken on the line 5—5 of Figure 1, and it will be noted that the upper and lower walls of the recesses 41 and 42 are much closer together at this point than is shown in Figure 4, which is taken at the point 4—4.

As the jar passes off from the rotating disk 34, it will be supported by the lower wall of the recess in the rotating member 1, and the lower wall of the recess in the curved cam member 13. As the jar continues its travel the rotation of the member 1 will cause the jar to rotate along the cam ledge so that every part of the flange of the jar and the cap will be presented to the cam ledge. As the recess in the cam ledge grows narrow, the lower portion of the flange of the cap will be gradually tucked underneath the shoulder 43 at the mouth of the jar until the cap is finally drawn down tight on to the jar and the flange fully turned underneath the ledge, as clearly shown in Figure 5. Inasmuch as the jar is supported during the closing of the same, there is no pressure upon the body of the jar. The upper part of the rotating member 1 is yieldingly pressed downwardly by the spring 11 and, therefore, these parts will yield to prevent the breaking of the jar mouth, but the pressure is sufficient to aid in the rotating of the jar and in the folding of the metal underneath the shoulder on the jar. Likewise, the

lower part of the curved cam 13 may yield, so as not to crush the mouth of the jar, but the springs are of sufficient tension to cause the gradual turning of the metal of the flange underneath the shoulder on the jar.

From the above it will be apparent that I have provided a machine wherein the jars travel continuously in a curved path, and may follow one upon the other without any special timing, which is quite an essential feature in this type of machine. These jars are supported by the ledge at the mouth of the jar during the closing operation and as the jar travels it is rotated so as to bring the flange of the cap at all parts thereof into contact with the cam ledge and this cam ledge gradually tucks the lower portion of the flange underneath the shoulder at the mouth of the bottle. After the caps have been secured to the jar they are again delivered on to the rotating disk 34 and carried out through the guiding passage between the member 25 and the end 24 of the cam ledge 13. The jars engage a guiding arm 50 and are directed off from the disk 34 on to the endless conveyor 31, so that the endless conveyor brings the jars to the machine and carries the closed jars away from the machine. This guiding arm 50 is formed with a shank 51 and is secured by bolts 52 to the supporting member 25. The lower member 25^b of the supporting member 25 is provided with a slot and also with a recess, as clearly shown in dotted lines in Fig. 2 of the drawings. The heads of the bolts 52 are sunk in the recesses and the bolts extend through the shank 51 of the arm 50 and thus it is that the shank is bolted to the lower member 25^b, so that the members 25^a and 25^b can yield one relative to the other. By loosening the bolts 52 the guiding arm can be shifted one way or the other, as desired.

While I have described and shown in Figures 4 and 5 a jar closure wherein the cap is bent underneath a shoulder on the jar, it will be obvious that my machine, by changing the form of the recesses in the rotating member 1 and in the curved cam ledge 13, readily adapts itself for use in closing other types of jars. For example, in Figures 6 and 7, I have shown a jar 47 having a substantially straight outer wall. The cap 48 is provided with a flange formed with a pocket in which is placed a sealing ring or gasket 49. The sealing of the jar is brought about by changing the shape of the pocket in the metal flange containing the rubber sealing ring or gasket. In this form of the invention the jar is supported by the table. It will, however, be rotated by the rotating member 1 and the cam ledge 13 has its recess shaped so as to gradually reshape the flange and force the gasket into gripping contact with the side wall of the jar. Here too, the members on the rotating member 1

and the cam ledge 13^b may yield to prevent the crushing of the jar which at the same time will bring about the proper reshaping of the flange to bring about a proper seal. It will be obvious, of course, that my improved closing means may be readily adapted for closing in vacuum.

It will be obvious that minor changes in the details of construction and arrangement of parts may be made without departing from the spirit of the invention as set forth in the appended claims.

Having thus described my invention, what I claim as new and desire to secure by Letters Patent is:

1. A glass jar closing machine including in combination a circular rotating member adapted to engage the flange of the cap for rotating the jar and cap, a cam ledge curved to conform to said circular member and spaced therefrom so as to engage the flange of the cap at the opposite side of the jar from the rotating member, said curved cam ledge including upper and lower members yieldingly pressed toward each other and having recesses formed therein adapted to receive the flange of the cap for turning the metal in the flange underneath the ledge on the jar for securing the cap to the jar.

2. A glass jar closing machine including in combination a circular rotating member adapted to engage the flange of the cap for rotating the jar and cap, a cam ledge curved to conform to said circular member and spaced therefrom so as to engage the flange of the cap at the opposite side of the jar from the rotating member, said circular rotating member including upper and lower members yieldingly pressed toward each other and having their adjacent faces formed with recesses to receive the flange of the cap, said curved cam ledge being constructed with a recess adapted to reshape the metal in the flange of the cap for securing the cap to the jar.

3. A glass jar closing machine including in combination a circular rotating member adapted to engage the flange of the cap for rotating the jar and cap, a cam ledge curved to conform to said circular member and spaced therefrom so as to engage the flange of the cap at the opposite side of the jar from the rotating member, said curved cam ledge including upper and lower members yieldingly pressed toward each other and having recesses formed therein adapted to receive the flange of the cap for turning the metal in the flange underneath the ledge on the jar for securing the cap to the jar, said rotating member being constructed so as to co-operate with said cam ledge in supporting the jar by the ledge at the mouth of the jar while the jar is being closed.

4. A jar closing machine including in combination, a circular rotating member adapted

- to engage the flange of a cap, a cam ledge 45 curved to conform to said circular member and spaced therefrom so as to engage the flange of the cap at the opposite side of the jar from said rotating member, said curved cam ledge being constructed so as to reshape the metal in the flange of the cap for securing the cap to the jar, said circular member and said cam ledge having yielding parts.
- 5 10 5. A jar closing machine including in combination, a circular rotating member having a recess formed in the edge thereof, a cam ledge curved to conform to said rotating member and spaced therefrom and including 15 upper and lower members yieldingly pressed toward each other and having a recess formed in their adjacent inner edges opposed to the recess in the edge of the rotating member, said recesses being shaped so as to receive the flange of a cap on a jar, so that 20 said rotating member will cause the jar to travel and rotate along said cam ledge and so that said cam ledge will turn the metal at the lower portion of the flange underneath 25 the jar shoulder at the mouth of the jar.
- 6 30 6. A jar closing machine including in combination, a circular rotating member having a recess formed in the edge thereof, a cam ledge curved to conform to said rotating member and spaced therefrom and having a recess formed in its inner edge opposed to the recess in the edge of the rotating member, said recesses being shaped so as to receive the flange of a cap on a jar, so that 35 said rotating member will cause the jar to travel and rotate along said cam ledge and so that said cam ledge will turn the metal at the lower portion of the flange underneath the jar shoulder at the mouth of the jar, and 40 said circular rotating member and said cam ledge being each formed with yielding sections.
- 7 40 7. A jar closing machine including in combination, a circular rotating member adapted
- to engage the flange of the cap, a cam ledge 45 curved to conform to said member and spaced therefrom so as to engage the flange of the cap at the opposite side of the jar, said rotating member and said cam member having opposed recesses formed in their adjacent edges, a guiding member having a recess in its edge for directing the jar with the cap thereon into the recess in the rotating member, a rotating disk for moving said jar into engagement with the rotating member, 50 said rotating member operating to rotate the jar and convey the same through the machine, and said cam ledge being constructed of yielding members adapted to engage and reshape the metal in the flange as the cap is 55 rolled along the same to cause said cap to be attached to the jar.
- 8 55 8. A jar closing machine including in combination, a circular rotating member adapted to engage the flange of the cap, a cam ledge 60 curved to conform to said member and spaced therefrom so as to engage the flange of the cap at the opposite side of the jar, said rotating member and said cam member having opposed recesses formed in their adjacent edges, a guiding member having a recess in its edge for directing the jar with the cap thereon into the recess in the rotating member, a rotating disk for moving said jar into engagement with the rotating member, 65 said rotating member operating to rotate the jar and convey the same through the machine, said cam ledge being constructed of yielding members adapted to engage and reshape the metal in the flange as the cap is 70 rolled along the same to cause said cap to be attached to the jar, and said disk being adapted to receive the jars after they have passed through the machine and move the same away from the rotating member. 75

In testimony whereof, I affix my signature.

THOMAS LUCIEN TALIAFERRO.
